ARC LAMP

Arthur J. Hatch, Toledo, Ohio, assignor to The Strong Electric Corporation, Toledo, Ohio, a corporation of Delaware

Application September 14, 1950, Serial No. 184,837

15 Claims. (Cl. 314—63)

1

My invention relates to arc lamps, and the principal object of my invention is to provide mechanism effective to maintain the arc both of proper quality and substantially at a predetermined location.

In the drawings accompanying this specification and forming part of this application I have shown for purposes of illustration what I now consider to be the best mode of carrying my invention into practice, and in these drawings:

Figure 1 is a side view of an arc lamp incorporating the within described embodiment of my invention, but omitting the near side door of the lamp to afford a view of part of the interior of the lamp;

Figure 2 is a plan view of a portion of the interior of the lamp of Figure 1;

Figure 3 is a diagrammatic representation of the mechanical and electrical arrangements; and

Figure 4 is a further view of the particular light-responsive means herein shown and described.

My invention is especially applicable to arc lamps of those types wherein the lamp comprises one or more reflectors or lenses or the like, constituting with the arc an optical system designed to produce a desired light formation, wherefore it is necessary that the arc be maintained substantially at a predetermined location, in order to maintain proper coordination between the arc and the remainder of the optical system.

Commonly such lamps are designed for operation on direct current, and to produce the great preponderance of the light at a crater in the end of the positive electrode, and to utilize particularly the light emitted from the crater, and in such instances maintaining the arc in proper coordination with the remainder of the optical system obviously is a matter of maintaining the crater of the positive electrode substantially at the predetermined properly cooperating position.

Accordingly, although my invention is not limited thereto, I have here illustrated it in respect of a lamp of the above recited characteristics, and therefore as functioning to automatically maintain both proper spacing of the electrodes and the crater of the positive electrode substantially at the predetermined optimum position.

Thus I have shown in the drawings a lamp 16 comprising a housing 11 containing a platform 12 on which are mounted a positive supporting and feeding mechanism 26 carrying a positive electrode 21, and a negative electrode supporting and feeding mechanism 36 carrying a nega-

2

tive electrode 31 disposed approximately forty-five degrees out of line with the positive electrode 21 and between which and the positive electrode 21 occurs the arc resulting in the emission of light particularly from the crater 22 at the forward end of the positive electrode 21.

In the present instance the light emitted particularly from the crater 22 of the positive electrode 21, is directed by a reflector 13 to a lens or lenses, not shown, located in a cone 14 extending from the front end of the lamp 16, and therefore the electrode mechanisms 20 and 30 are operated and controlled to maintain proper spacing of the electrodes and thus proper quality of the arc, and to maintain the crater 22 of the positive electrode 21 substantially in the predetermined position of proper optical coordination with the reflector 13.

In the described embodiment the positive electrode mechanism 20 comprises three rollers 23, rotated to effect rotation of the positive electrode 21 to cause the electrode 21 to burn evenly, and skewed to simultaneously effect appropriate longitudinal movement of the electrode 21, and the negative electrode mechanism 30 comprises a reciprocable electrode holder 32 carrying the negative electrode 31 and reciprocable by means of a suitable screw 33.

As indicated particularly in Figure 2, in the present embodiment the positive electrode rollers 23 are driven from a positive electrode drive shaft 24 operated by a positive electrode feed motor 25 through a suitable speed reduction mechanism 26 and a clutch 27 provided to permit adjustment of the positive electrode 21 by operation of a suitable hand crank 28, and similarly the negative electrode screw 33 is driven from a positive electrode drive shaft 34 operated by a negative electrode motor 35 through a suitable speed reduction mechanism 36 and a clutch 37 provided to permit adjustment of the negative electrode 31 by operation of a suitable hand crank 38.

Further, as indicated in Figure 3, in the present embodiment the positive electrode 21 is supplied by a main positive conductor 40 extending to a main positive terminal 41, the negative electrode 31 is supplied by a main negative conductor 50 extending to a main negative terminal 51, the positive electrode feed motor 25 comprises an armature 42 connected directly across the main positive and negative conductors 40 and 50 and a field 43 connected across the main conductors 40 and 50 in series with an adjustable rheostat 44 and a control resistor 45, and the negative

electrode feed motor 35 comprises an armature 52 connected directly across the main conductors 49 and 53 and a field 53 connected across the conductors 49 and 53 in series with an adjustable rheostat 54 and a control resistor 55.

With the foregoing the lamp 10 comprises means responsive to the position of the crater 22 of the positive electrode 21, normally shunting the negative control resistor 55, but operating upon movement of the crater 22 into position in advance of the correct optical location, to no longer shunt the negative control resistor 55, and to shunt the positive control resistor 45, thereby strengthening the positive motor field 43 and decreasing the speed of the positive motor 25 and the rate of feed of the positive electrode 21, thus to restore the crater 22 to its proper location, and simultaneously weakening the negative motor field 53 and increasing the speed of the negative motor 35 and the rate of feed of the negative electrode 31, thus nevertheless to maintain proper spacing of the electrodes 21 and 31 and proper quality of the arc.

According to my present preference the above means comprises an electromagnetic switch 60 of suitable construction, a light-responsive device 70 of the type shown in my copending application Serial Number 157,575, filed April 22, 1950, and a lens 15 arranged to direct light from the crater 22 to the device 70.

Specifically the present switch 60 comprises a contact 61 connected to the positive motor field circuit ahead of the positive control resistor 45, a contact 62 connected to the negative motor field circuit ahead of the negative control resistor 55, a contactor 63 connected to the return from the control resistors 45 and 55 and biased to be normally in engagement with the negative contact 62, thereby shunting the negative control resistor 55, and an operating coil 64 energized under control of the device 70 and constructed and arranged thereupon to move the contactor 63 from the contact 62 to the contact 61 and thereby transfer the shunt from the negative control resistor 55 to the positive control resistor 45.

Similarly the herein illustrated light-responsive device 70 comprises a base 71 provided with terminal pins 72 and 73, a glass bulb 14 closed to the base 71 and provided with a coating 75 relatively impervious to light but containing a window 76, and a bi-metallic element 77 carried by the one terminal pin 72, comprising a forwardly extending arm 77a, a substantially inflexible cross-piece 77b, and a reversely extending arm 77c carrying a contact 78 arranged to engage a relatively stationary cooperating contact 79 carried by the other terminal pin 73.

With the foregoing the parts are so constructed and arranged that when the crater 22 of the positive electrode 21 is substantially at its optimum location, light from the crater 22 to the lens 15 will fall upon the forwardly extending arm 77a of the bi-metallic member 77, heating that arm and causing that arm to flex, resulting in moving and holding the member contact 78 away from and out of engagement with the cooperating contact 79.

On the other hand, when the crater 22 becomes appreciably in advance of its optimum location, the light to the lens 15 will then fall on the reversely extending arm 77c, heating that arm and causing that arm to flex, resulting in moving the member contact 78 into engagement with the cooperating contact 79, thus energizing the coil 64 of the electromagnetic switch 60.

resulting in decreasing the speed of the positive motor 25 and the rate of feed of the positive electrode 21, and in commensurately increasing the speed of the negative motor 35 and the rate of feed of the negative electrode 31.

In the present embodiment a resistor 16 is connected across the terminals of the light-responsive device 70 for the purpose of decreasing arcing when the free end 79 of the element 77 breaks engagement with the cooperating contact 79, and a signal lamp 17 is connected across a resistor 18 interposed in the connection from the negative switch contact 62, thereby to be energized when the switch 60 is in normal position and not energized when the switch 60 is in the alternate position, thus to visually indicate the condition of the apparatus.

As herein shown the foregoing electrical connections are accomplished by a conductor 80 extending from the main positive conductor 40 to one terminal of the positive motor armature 42, one terminal of the positive motor field 43, one terminal of the negative motor armature 52, and one terminal of the negative motor field 53, a conductor 81 extending from the other terminal of the positive motor field 43 to the movable contact of the positive adjusting rheostat 64, a conductor 82 extending from the second terminal of the negative motor field 53 to the movable contact of the negative adjusting rheostat 54, a conductor 83 extending from the fixed terminal of the positive adjusting rheostat 44 to one terminal of the positive control resistor 45 and to the positive contact 61 of the switch 60, a conductor 84 extending from the fixed terminal of the negative adjusting rheostat 54 to one terminal of the negative control resistor 55 and to one terminal of the lamp resistor 18, a conductor 85 extending from the terminal of the resistor 18 to one terminal of the signal lamp 17, a conductor 86 extending from the other terminal of the lamp 17 to the second terminal of the resistor 18, a conductor 87 extending from the second terminal of the resistor 18 to the negative contact 62 of the switch 60, a conductor 88 extending from the main positive conductor 40 to the terminal pin 72 of the light-responsive device 70 and to one terminal of the shunting resistor 18, a conductor 89 extending from the other terminal of the resistor 16 and the terminal pin 73 of the device 70, to one terminal of the coil 64 of the switch 60, and a return conductor 90 connecting to the main negative conductor 50 the second terminal of the positive motor armature 42, the second terminal of the positive control resistor 45, the second terminal of the switch control resistor 45, the second terminal of the switch coil 64, the contactor 63 of the switch 60, the second terminal of the negative control resistor 55, and the second terminal of the negative motor armature 52.

With the above arrangement the positive adjusting rheostat 44 is set to the position whereby with the switch 60 in normal position the positive electrode 21 will be fed at a rate slightly greater than the rate at which it is to be consumed, and the negative adjusting rheostat 54 is set to provide that the negative electrode 31 will be fed at a rate to maintain proper spacing of the electrodes and proper quality of the arc.

Under these conditions, the crater 22 of the positive electrode 21 will be gradually advanced beyond its predetermined location; however, before this advance has become sufficient to affect proper optical coordination of the crater 22

with the remainder of the optical system, the light from the crater 22 to the lens 15 will become transferred from the forwardly extending arm 71a to the reversely extending arm 71c of the bi-metallic element 71, resulting in engagement of the element contact 78 with the cooperating contact 79, closing the circuit through the coil 64 of the electromagnetic switch 60, and shifting the electromagnetic contactor 63 from engagement with the negative contact 62 to engagement with the positive contact 61, transferring the shunt from the negative control resistor 55 to the positive control resistor 45.

The control resistors 45 and 55 being of proper values, thereupon the positive electrode 21 will be fed at a rate slightly less than the rate at which it is being consumed, and the negative electrode 31 will be fed at a rate greater than the rate at which it is being consumed, and such that the combined rates of feed of the two electrodes 21 and 31 continue to be equal to the combined rate at which they are being consumed and thus the quality of the arc continues to be maintained.

Thereby the crater 22 will gradually recede to the predetermined point, whereupon the lens 15 will no longer direct light upon the reversely extending arm 71c, the element contact 78 will withdraw from engagement with the cooperating contact 79, the circuit through the switch coil 64 will be interrupted, the switch contactor 63 will return from the positive contact 61 to the negative contact 62, and the shunt will be returned from the positive control resistor 45 to the negative control resistor 55, and the entire mechanism will be restored to its previous condition.

As will be understood, the foregoing will occur repeatedly, and thus the described mechanism will operate to automatically maintain both the quality of the arc and the arc at the proper location.

However, within any usual limits of variation of rate of feed of the positive electrode 21, the corresponding variation in the rate of feed of the negative electrode 31 is less than the amount by which the rate of feed of the negative electrode may be satisfactorily varied at each cycle of the automatic variation by operation of the switch 60 and its associated mechanisms.

Thus under normal circumstances it is not necessary to adjust the rate of feed of the negative electrode 31 consequent to adjustment of the rate of feed of the positive electrode 21, and therefore in the present embodiment the negative control resistor 55 is constructed of proper value, and for automatic operation of the lamp the negative resistor 54 is set and remains at zero.

Thus the only adjustment is of the positive adjusting rheostat 44, according to the rate at which the positive electrode 21 is to be consumed, and further, the rheostat 44 may be scaled directly, either in terms of rate of consumption of the positive electrode, or in terms of the corresponding currents, or however may be desired.

Therefore the described embodiment adequately accomplishes at least the principal object of my invention, and on the other hand, obviously various changes and modifications may be made, and therefore my invention is not to be regarded as limited to the particular embodiment herein shown and described, and I claim as my invention:

1. An arc lamp comprising two electrodes constructed and arranged to function as terminals 75

of an arc, means constructed and arranged to automatically and continuously feed said electrodes each at a substantially constant rate, capable of change of the ratio between the respective rates of feed, and comprising a first electric motor connected to continuously feed one of said electrodes, a second electric motor connected to continuously feed the other of said electrodes, a first resistance connected to alter the speed of the first motor, a second resistance connected to alter the speed of said second motor, and an electric switch normally rendering said first resistance operative and not said second resistance, movable to a position rendering said second resistance operative and not said first resistance, and means constructed and arranged to automatically shift said switch responsive to change in position of the arc.

2. An arc lamp comprising two electrodes constructed and arranged to function as terminals of an arc, means constructed and arranged to automatically and continuously feed said electrodes each at a substantially constant rate, adjustable to change the rate of feed of one of said electrodes, capable of change of the ratio between the respective rates of feed, and comprising a first electric motor connected to continuously feed one of said electrodes, a second electric motor connected to continuously feed the other of said electrodes, a first resistance connected to alter the speed of said first motor, a second resistance connected to alter the speed of said second motor, and an electric switch normally rendering said first resistance operative and not said second resistance, movable to a position rendering said second resistance operative and not said first resistance, and means constructed and arranged to automatically shift said switch responsive to change in position of the arc.

3. An arc lamp comprising two electrodes constructed and arranged to function as terminals of an arc, means constructed and arranged to automatically and continuously feed said electrodes substantially at the rate at which said electrodes will be consumed at the current at which the lamp is desired to be operated, thereby to automatically maintain the quality of the arc, and to normally feed said electrodes at respective rates defining a ratio somewhat different from the ratio at which said electrodes will be consumed at such current, and capable of change of said ratio to a ratio also somewhat different from the ratio at which said electrodes will be consumed at such current but departing in the inverse direction, said means comprising a first electric motor connected to continuously feed one of said electrodes, a second electric motor connected to continuously feed the other of said electrodes, a first resistance connected to alter the speed of said first motor from the speed of the first said ratios to the speed of the second said ratios, a second resistance connected to alter the speed of said second motor from the speed of the second said ratio to the speed of the first said ratio, an electric switch normally rendering said first resistance operative and not said second resistance, movable to a position rendering said second resistance operative and not said first resistance, and means constructed and arranged to automatically shift said switch responsive to change in position of the arc.

4. An arc lamp comprising two electrodes constructed and arranged to function as terminals of an arc, means constructed and arranged to automatically and continuously feed said electrodes each at a substantially constant rate, and means

constructed and arranged to automatically maintain the arc substantially at a given position, said means comprising a first electric motor connected to continuously feed one of said electrodes, a second electric motor connected to continuously feed the other of said electrodes, a first resistance connected to alter the speed of said first motor, a second resistance connected to alter the speed of said second motor, and an electric switch normally rendering said first resistance operative and not said second resistance, movable to a position rendering said second resistance operative and not said first resistance, and means constructed and arranged to automatically shift said switch responsive to change in position of the arc.

5. An arc lamp to operate on direct current, comprising a positive electrode and a negative electrode constructed and arranged to form the terminals of an arc, means constructed and arranged to automatically and continuously feed said electrodes each at a substantially constant rate, capable of change of the ratio between the respective rates of feed, and comprising a first electric motor connected to continuously feed one of said electrodes, a second electric motor connected to continuously feed the other of said electrodes, a first resistance connected to alter the speed of said first motor, a second resistance connected to alter the speed of said second motor, and an electric switch normally rendering said first resistance operative and not said second resistance, movable to a position rendering said second resistance operative and not said first resistance, and means constructed and arranged to automatically shift said switch responsive to change in position of the arc and thereby to automatically maintain the arc substantially at a given position.

6. An arc lamp comprising two electrodes constructed and arranged to function as terminals of an arc, means constructed and arranged to automatically and continuously feed said electrodes each at a substantially constant rate, capable of change of the ratio between the respective rates of feed, and comprising a first electric motor connected to continuously feed one of said electrodes, a second electric motor connected to continuously feed the other of said electrodes, a first resistance in series with the field of said first motor, a second resistance in series with the field of said second motor, and an electric switch normally shunting said first resistance and not said second resistance, movable to a position shunting said second resistance and not said first resistance, and means constructed and arranged to automatically shift said switch responsive to change in position of the arc.

7. An arc lamp comprising two electrodes constructed and arranged to function as terminals of an arc, means constructed and arranged to automatically and continuously feed said electrodes each at a substantially constant rate, adjustable to change said rate, capable of change of the ratio between the respective rates of feed, and comprising a first electric motor connected to continuously feed one of said electrodes, a second electric motor connected to continuously feed the other of said electrodes, a first rheostat connected to adjust the speed of said first motor, a second rheostat connected to adjust the speed of said second motor, a first resistance connected to alter such speed of said first motor, a second resistance connected to alter such speed of said second motor,

10 and an electric switch normally rendering said first resistance operative and not said second resistance, movable to a position rendering said second resistance operative and not said first resistance, and means constructed and arranged to automatically shift said switch responsive to change in position of the arc.

8. An arc lamp comprising two electrodes constructed and arranged to function as terminals of an arc, means constructed and arranged to automatically and continuously feed said electrodes each at a substantially constant rate, adjustable to change said rate, capable of change of the ratio between the respective rates of feed, and comprising a first electric motor connected to continuously feed one of said electrodes, a second electric motor connected to continuously feed the other of said electrodes, a first rheostat connected to adjust the speed of said first motor, a first resistance in series with the field of said first motor, a second resistance in series with the field of said second motor, and an electric switch normally shunting said first resistance and not said second resistance, movable to a position shunting said second resistance and not said first resistance, and means constructed and arranged to automatically shift said switch responsive to change in position of the arc.

9. An arc lamp comprising two electrodes constructed and arranged to function as terminals of an arc, means constructed and arranged to automatically and continuously feed said electrodes each at a substantially constant rate, a single means operative to adjust the rate at which said electrodes will be consumed, and means constructed and arranged to automatically maintain the arc substantially at a given position at any rate at which said electrodes are adjusted to be consumed.

10. An arc lamp comprising two electrodes constructed and arranged to function as terminals of an arc, means constructed and arranged to automatically and continuously feed said electrodes each at a substantially constant rate and capable of change of the ratio between the respective rates of feed, and means constructed and arranged to automatically change said ratio in response to change in position of the arc.

11. An arc lamp comprising two electrodes constructed and arranged to function as terminals of an arc, means constructed and arranged to automatically and continuously feed said electrodes each at a substantially constant rate, adjustable to change said rate, and capable of change of the ratio between the respective rates of feed, and means constructed and arranged to automatically change said ratio in response to change in position of the arc and thereby to automatically maintain the arc substantially at a given position.

12. An arc lamp comprising two electrodes constructed and arranged to function as terminals of an arc, means constructed and arranged to automatically and continuously feed said electrodes each at a substantially constant rate, and means constructed and arranged to automatically maintain the arc substantially at a given position.

13. An arc lamp and control therefor including, in combination, two electrodes supported for relative movement, means for automatically feeding each of said electrodes at a substantially constant rate and capable of change of ratio be-

tween the respective rates of feed, said feeding means including a first electric motor adapted to continuously feed one of said electrodes, a second electric motor adapted to continuously feed the other of said electrodes, a first resistance connected to alter the speed of the first motor, a second resistance connected to alter the speed of the second motor, a shunt resistor connected with one of the resistances, switch means movable to a position for connecting the shunt resistor to the other of said resistances, and means responsive to the relative position of one of said electrodes for automatically actuating said switch.

14. An arc lamp and control therefor including, in combination, two electrodes supported for relative movement, means for automatically feeding each of said electrodes at a substantially constant rate and capable of change of ratio between the respective rates of feed, said feeding means including a first electric motor adapted to continuously feed one of said electrodes, a second electric motor adapted to continuously feed the other of said electrodes, a first resistance connected to alter the speed of the first motor, a second resistance connected to alter the speed of the second motor, a shunt resistor connected with one of the resistances, electrically actuated switch means movable to a position for connecting the shunt resistor with the other of said resistances to effect a change in rates of speed of the electrode feed motors, and energy-responsive means intercalated in the switch-actuating circuit to cause actuation of the switch upon change in position of the arc.

15. An arc lamp and control therefor including, in combination, two electrodes supported for relative movement, means for automatically feeding each of said electrodes at a substantially constant rate and capable of change of ratio between the respective rates of feed, said feeding means including a first electric motor adapted to continuously feed one of said electrodes, a second electric motor adapted to continuously feed the other of said electrodes, a first resistance connected to alter the speed of the first motor, a second resistance connected to alter the speed of the second motor, a shunt resistor connected with one of the resistances, said resistances in the motor circuits and said shunt resistor being arranged to maintain a constant combined rate of speed of said motors, electrically actuated switch means movable to a position for connecting the shunt resistor with the other of said resistances to increase the speed of one motor and decrease the speed of the other, and energy-responsive means intercalated in the switch-actuating circuit to cause actuation of the switch dependent upon the relative position of the arc.

ARTHUR J. HATCH.
